UNITED STATES PATENT OFFICE

2,305,522

SWIVEL SPOUT FOR METAL CONTAINERS

Henry A. Fink, Pelham Manor, N. Y., assignor to
 Continental Can Company, Inc., New York,
 N. Y., a corporation of New York

Application May 27, 1940, Serial No. 337,520

1 Claim. (Cl. 221—23)

The invention relates to new and useful improvements in a pouring spout for containers, and more particularly to the means for attaching a spout to the container end so that it may be forcibly shifted to different set positions on the container.

An object of the invention is to provide a means whereby the spout may be connected to the container end so that it may be shifted to different set positions thereon without in any way disturbing the tight sealing of the container.

A further object of the invention is to provide a means for connecting the pouring spout to a container which is so arranged that the friction plug may be inserted in the neck portion of the container to which the spout is attached.

A still further object of the invention is to provide a means for attaching a pouring spout to an upstanding neck portion formed integral with the container end, wherein the supporting means for the spout surrounds the neck portion, leaving the inner face of the neck portion free to serve as a seat for a friction plug.

A still further object of the invention is to provide a connecting means of the above type wherein the friction plug when inserted in the neck portion serves to retain the spout on the neck portion of the container.

These and other objects will in part be obvious and will in part be hereinafter more fully disclosed.

In the drawing—

Figure 1 is a vertical sectional view through the container showing my improved means for attaching the swivel spout to the closure member for the container;

Fig. 2 is an enlarged sectional view through the spout and the means for attaching the same to the closure end;

Fig. 3 is a plan view of a portion of the top of the container with the spout attached thereto and positioned for pouring;

Fig. 4 is a detail showing a modified form of means for attaching the spout to the container end; and

Fig. 5 is an enlarged sectional view showing another modified form of means for attaching the spout to the closure end.

The closure end for the container, whether it is of a friction plug type or an end which is double-seamed to the container body, is provided with a pouring opening located at one side of the center of the end so that when the pouring spout is associated therewith, it may be readily placed so that the extreme lip of the pouring spout will

project over the side wall of the container. The closure member has an upstanding cylindrical neck portion surrounding the pouring opening, which neck portion is preferably integral with the closure member. The spout is carried by a cylindrical supporting base which is so dimensioned that it engages the outer wall of the neck portion with a sufficient friction-tight contact so that the spout is held on the neck portion, but may be forcibly turned about the neck portion to different set positions, and this is why the spout is referred to as a swivel spout. This mounting of the supporting base portion of the spout on the outer face of the neck portion leaves the inner face of the neck portion free to receive the friction plug for closing the pouring opening.

Referring more in detail to the drawing, the container body is indicated at 1 and the top member indicated at 2 is in the form of a ring which is secured to the body wall in any suitable way, either by double-seaming or by soldering. As shown in the drawing, this end ring is provided with a flange or skirt which slips down over the outer surface of the container body and is soldered thereto. The ring at its inner side is provided with a depending friction wall 3 in which a closure member 4 is frictionally seated. This closure member 4 is provided with a pouring opening 5 which is surrounded by an upstanding cylindrical neck portion 6. This upstanding cylindrical neck portion is shown as integral with the end and of substantially uniform diameter.

The spout indicated at 7 is provided with a cylindrical supporting base 8 which is dimensioned so as to engage with a frictional fit the outer wall of the upstanding neck portion 6. The lower edge portion of this cylindrical base member 8 of the spout is curled outwardly and upwardly to strengthen the base portion. The spout extends outwardly from the base portion so that when positioned as shown in Figures 1 and 3, the extreme pouring lip 9 of the spout overhangs the ring top 2. The extreme outer edge of the spout terminates substantially directly over the wall of the container when the spout is in this pouring position. The spout has side walls 1a which merge into the supporting base. The upper edge portion of the supporting base at the side thereof opposite the spout is provided with an outwardly and downwardly turned flange 10 which also strengthens the spout. The frictional engagement between the spout and the neck is sufficient to hold the spout on the neck, but at the same time permits the spout to be forcibly turned about the neck to different set positions. In

other words, it may be positioned as shown in the drawing for pouring, or it may be shifted to a position wholly within the outer limits of the friction plug closure member 4.

The spout makes contact with the outer wall of the neck portion 6, leaving the inner wall free to serve as a friction seat for the closure plug 11. The closure plus 11 is provided with a bottom portion 12 and cylindrical side walls 13 terminating in an outwardly projecting flange 14 at the upper end thereof. This flange 14 is of sufficient width so that it overlies the spout as shown in Figures 1 and 2. Thus it is that the friction plug when inserted in the neck of the closure end serves as a means for retaining the spout on the neck.

It should be noted that the friction plug makes sealing contact with the neck portion of the closure member, and therefore, a very tight sealed joint is obtained. The plug may be withdrawn and replaced at will for opening and closing the container.

Instead of attaching the spout to a neck portion on a friction plug closure member, it may be attached to a neck portion formed on the end which is double-seamed to the can body, and therefore, the term "closure member" as used, is intended to apply either to an inserted friction plug, as shown in the drawing, or any other type of end member which may be seamed to the body portion of the container.

In Figure 4, the spout is shown as having a cylindrical supporting base 8 curled at 8a and flared outwardly at 8b. The neck portion 6 of the closure member is bent outwardly at 15 so as to provide a mechanical means for retaining the spout on the neck portion. This outwardly bent portion may be so dimensioned that the spout can be turned on the neck portion to different set positions.

As shown in Figure 5, the cylindrical base portion 8 of the spout is provided with a curl 8a at its lower portion. The neck portion 6 of the closure member, together with the cylindrical supporting base of the spout are beaded as in-

45 indicated at 16 so that the spout is locked against any endwise movement of the neck portion while it is permitted to be turned to different set positions on the neck portion.

5 It should be noted that in the construction shown in both Figures 4 and 5, the inner wall of the neck portion is free to form a frictional seat for the closure plug 11 which is of the construction described above in connection with Figures 1 to 3.

10 15 The means for attaching the spout to the closure member is free from seams so that the connection is very simple and can be readily made by forcing the spout down on to the neck portion as shown in Figures 1 to 3, and by the simple bending of the neck portion as shown in Figure 4, and by the simple beading of the neck and spout as shown in Figure 5. In all instances, the closure plug when seated makes a tight sealed contact for the container, and there is no chance for leakage through the connection between the spout and the closure member.

20 25 It is obvious that minor changes in the details of construction may be made without departing from the spirit of the invention as set forth in the appended claim.

Having thus described the invention, what I claim as new and desire to secure by Letters Patent, is:

30 35 40 The combination of a closure member for a sheet metal container having a pouring opening therethrough surrounded by an upstanding cylindrical neck portion, a pouring spout having a cylindrical supporting member adapted to surround said neck portion making limited frictional engagement therewith so as to permit a shifting of the spout to different set positions on said neck portion, and a closure plug adapted to frictionally engage within said neck portion for closing the opening therethrough, said closure plug having a projecting flange at the upper end thereof adapted to extend over the pouring spout for retaining the spout on the neck portion when the plug is in sealing position.

45 HENRY A. FINK.
